UNITED STATES PATENT OFFICE.

ARTHUR THOMAS KELLY, OF OKLAHOMA, OKLAHOMA.

COLLAPSIBLE ICE-PICK.

1,298,961.

Specification of Letters Patent.

Patented Apr. 1, 1919.

Application filed June 8, 1918. Serial No. 238,865.

To all whom it may concern:

Be it known that I, ARTHUR THOMAS KELLY, a citizen of the United States, residing at Oklahoma, in the county of Oklahoma and State of Oklahoma, have invented 5 certain new and useful Improvements in Collapsible Ice-Picks, of which the following is a specification.

This invention relates to collapsible ice 10 picks.

The primary object of this invention is to provide a device or tool of this character in which the pick may be folded back in an out-of-the-way position against the 15 handle when the pick is not in use.

A further object of the invention is to provide means to hold the pick in either extended (operative) position or in folded position, as desired.

20 A still further object of my invention is to provide a handle adapted to constitute a carrier and scabbard for a number of extra picks.

With the foregoing and other objects in 25 view that will appear as the nature of the invention is better understood, the same consists in the novel features of construction, combination and arrangement of parts illustrated in the drawings and more particularly pointed out in the appended claim.

30 In the accompanying drawings:—

Figure 1 is an edge view of an ice pick, embodying my improvements.

Fig. 2 is a side elevation thereof.

35 Fig. 3 is a detail fragmentary view of the ice pick and the upper end of the handle, on an enlarged scale, with parts shown in section.

Fig. 4 is a detail fragmentary sectional view, taken at right angles to Fig. 3 and Fig. 40 5 is a detail fragmentary longitudinal section of the lower end of the ice pick and the pick head.

45 Referring to the drawings for a more particular description of the invention and which drawings are for illustrative purposes only and are therefore not drawn to scale, 1 designates the ice pick and 2 the handle. The handle 2, which is preferably formed of 50 wood and gradually tapers from its outer to its inner end, is provided at its outer end with a bearing head 3, consisting of a pair of corresponding laterally spaced flat bearing plates 4 connected at their outer edges 55 by the transverse strip 5 and formed with rounded or curved outer edges 6 which pro-

ject beyond the plane of the adjacent side of the handle.

A pick head 7 is pivoted, as at 8, in the bearing head 3 and comprises a hollow substantially tubular sleeve 9 which receives the inner end of the pick 1. The pick head is further provided with a pivoted catch 10 adapted to engage and hold the pick in removable position therein, as shown. 60

The body portion, as 11, of the pick head, is provided in its inner edge with a transverse recess 12 and in its outer or opposite edge with a corresponding recess 13, either of which is adapted to receive the cross bar 70 14 of the locking member 15, the purpose of which will presently appear. The longer bar 16 of the locking member 15 extends longitudinally of the handle and is formed on a gradual outward curve, said locking member 75 being hinged or pivoted at the junction of its longer and shorter arms or bars, as at 17, to the bearing plate 4, in any suitable way. As shown, the outer or free end of the cross bar 14 of the locking member 80 extends beyond the other bearing plate 4 of the bearing head 3 and terminates in an outwardly bent lug 18 which bears against the inner free end of a flat metallic spring 19, the tendency of which is to hold the locking 85 member in inoperative position.

In carrying out the invention, the bearing plate 4 is provided with an elongated extension 20 which bears against and is secured to the adjacent portion of the handle. Said 90 extension 20 is provided at its longitudinal edges with the inwardly bent or inturned flanges 21 and forms a guide bearing for the slid able keeper or clip 22 which receives and works against the longer arm or bar of 95 the locking member.

In practice, to hold the pick in either operative or folded position, as desired, the clip or keeper 22 is slid inwardly in the extension 20 of the bearing plate 4 which depresses the longer arm or bar of the locking member and throws the cross bar thereof outwardly into engagement with either the recess 12 or 13 in the pick head, as the case may be. To swing the pick from extended 100 or operative position into folded position, or vice versa, the clip or keeper is moved outwardly in its guide bearing, when the cross bar of the locking member is disengaged from the pick head by the action of 110 the spring 19. After the pick is positioned or swung into the position desired, the lock-

ing member is again secured or retained in normal or locking position by again sliding the clip or keeper 22 inwardly in its guide bearing 20 before mentioned.

5 The tool is also provided at one side with a holder 23 formed with an inwardly bent hook 24 adapted to slip over the belt strap or the trousers for convenience in carrying.

10 The handle is also provided with a plurality of longitudinal grooves 25 to receive and hold a number of extra picks, and with a hollow removable screw threaded cap 26 at its inner end to provide ready and convenient access to the same.

15 From the foregoing description taken in connection with the drawings, it is thought that the construction, operation and advantages of this invention will be readily understood without requiring a more extended 20 explanation.

Various changes in the form, proportions and minor details of construction may be

resorted to without departing from the principles or sacrificing any of the advantages of this invention as defined in the appended 25 claim.

Having described my invention, what I claim as new and desire to secure by Letters Patent, is:—

A device of the character specified comprising a handle, a bearing head at the outer end of the handle, a pick pivoted in said bearing head and adapted to fold in against the handle, means comprising a right angled locking member pivoted to the bearing head 35 for securing the pick in either extended operative position or folded inoperative position, a spring tending to hold the locking member in inoperative position and a clip or keeper engaging the longer arm of the 40 locking member for securing the latter in locking position.

In testimony whereof I affix my signature.

THOMAS KELLY.
